12 Claims

ABSTRACT OF THE DISCLOSURE

A fluid pump assembly of the steam injection type consisting of a tank having a top chamber and a bottom chamber. The bottom chamber contains a boiler portion with an electric heater. A float valve mounted in the bottom chamber controls admission of steam into the bottom chamber from the boiler portion. Tandem-operating valves are provided in the top walls of the top and bottom chambers. The top valve is normally open and elevated and contains a capsule containing mercury which expands responsive to heat, moving the valve from open to closed position. This also closes the bottom valve. Steam from the bottom chamber can enter the top chamber and acts on the mercury capsule to cause the two valves to close. Trapped steam in the top chamber condenses, creating a vacuum. The top chamber is connected to a liquid source. The vacuum draws the liquid into the top chamber, causing the mercury capsule to cool and causing fluid pressure to be developed in the top chamber, whereby to re-open the tandem valves. The liquid flows into the bottom chamber, acting on the float valve to cut off the flow of steam when the level in the bottom chamber reaches a desired height. The assembly is provided with a hot-and-cold fluid-mixing outlet conduit system connected to the bottom chamber.

This invention relates to fluid distribution systems, and more particularly to a fluid pump assembly of the steam injection type which may be employed for the purpose of pumping fluids of various types, such as water, gas, oil, or the like, from a source to a distribution conduit system or other destination.

A main object of the invention is to provide a novel and improved fluid pump of the steam injection type, the pump being relatively simple in construction, being reliable in operation, and being adaptable for use with a wide range of fluids. Thus, the pump assembly may be used to convey liquid, such as a refined sea water for long distances, or may be used as a pumping part of a pipeline system.

A further object of the invention is to provide an improved pumping system for delivering fluids, such as water, gas, oil, or the like, from a supply source to a distributing conduit system, the pump involving relatively few moving parts, being relatively compact in size, being economical to operate, and requiring a minimum amount of maintenance attention to keep it in operating condition.

A still further object of the invention is to provide an improved fluid pump of the steam injection type for pumping liquids, such as water, gas, oil, or the like, the pump being inexpensive to fabricate, being inexpensive to operate, being provided with emergency operating means which may be used in the event that the main source of power for the pump breaks down, and being provided with a mixing system for regulating the temperature of liquid withdrawn therefrom.

A still further object of the invention is to provide an improved fluid pump of the steam injection type which employs a control valve system which is thermally-operated in a novel and highly efficient manner, the pump

2

valve system thereby being reduced to a relatively small number of parts and being adapted for long periods of operation without the need for frequent inspection or repair.

Further objects and advantages of the invention will become apparent from the following description and claims, and from the accompanying drawings, wherein:

FIGURE 1 is a vertical cross-sectional view taken through an improved fluid pump assembly constructed in accordance with the present invention.

FIGURE 2 is an enlarged vertical cross-sectional view taken through an upper corner portion of the assembly of FIGURE 1, and particularly showing the construction of the actuating mechanism for the tandem valves of the pump.

FIGURE 3 is a horizontal cross-sectional view taken substantially on the line 3—3 of FIGURE 2.

FIGURE 4 is a horizontal cross-sectional view taken substantially on the line 4—4 of FIGURE 2.

FIGURE 5 is an enlarged fragmentary vertical cross-sectional view taken substantially on the line 5—5 of FIGURE 4.

FIGURE 6 is an enlarged horizontal cross-sectional view taken substantially on the line 6—6 of FIGURE 1.

FIGURE 7 is a vertical cross-sectional view taken substantially on the line 7—7 of FIGURE 6.

FIGURE 8 is an enlarged fragmentary vertical cross-sectional view taken substantially on the line 8—8 of FIGURE 1.

FIGURE 9 is a fragmentary horizontal plan view taken substantially on the line 9—9 of FIGURE 8.

FIGURE 10 is a vertical cross-sectional view taken substantially on the line 10—10 of FIGURE 8.

Referring to the drawings, 11 generally designates an improved pump assembly, constructed in accordance with the present invention, employed for the purpose of pumping water from a supply source 12 to a distribution system, for example, to the water distribution system of a dwelling. Thus, the pump assembly may be located in any convenient portion of the dwelling, for example, in the basement, and the pump assembly is connected to the water supply source 12 by any suitable type of conduit, such as the conduit 13 shown in FIGURE 1. The pump assembly has an outlet conduit 14 for general distribution, and is further provided with a hot-and-cold water-mixing system, designated generally at 15, presently to be described in detail.

The fluid pump assembly 11 comprises a tank 16 which is provided with an intermediate horizontal partition wall 17 which divides the tank into a top chamber 18 and a bottom chamber 19. The water inlet conduit 13 is connected to top chamber 18 at the top wall 20 of said top chamber, as is clearly shown in FIGURE 1. The conduit 13 extends to the supply reservoir 12, whose top surface may be on a level substantially lower than that of top wall 20, as shown.

The lower portion of tank 16 includes a boiler chamber 21 which communicates with the lower chamber 19 through a horizontal conduit 22 mounted on the bottom wall 23 of the tank and extending through the lower marginal portion of the main wall of the tank. Thus, the boiler chamber 21 comprises a lateral extension of the lower portion of the tank. However, it communicates with the lower chamber 19 of the tank.

A conventional electric heating unit 24 is provided at the bottom of boiler chamber 21 immediately beneath conduit 22, as shown in FIGURES 1, 8 and 10. The heating unit 24 includes the generally semicylindrical opposing inner segments 25, 25 which are mounted in the conduit 22 and which are separated by a mass of refractory material 26 through which extends suitable heater wind-

ings (not shown), forming part of the heater assembly. Thus, the inner sections 25, 25 define a pair of water-flow channels leading from chamber 19 to the interior of boiler chamber 21.

Conduit 22 has an end wall 27 located in chamber 19, but is provided with an aperture 28 in its top wall opening into chamber 19 and allowing the water in chamber 19 to enter conduit 22 and flow therethrough in the generally semicylindrical opposing sections 25, 25 to the interior of boiler chamber 21. The heater windings extend around the conduit sections 25, 25 and also between their adjacent inside walls 29, 29. Thus, the heat-conducting conduit sections 25, 25 provide sufficient conduction of heat from the heater windings to the water flowing through the conduit sections to keep the water boiling.

Boiler chamber 21 is provided with a hot water outlet conduit 30 leading to the mixing valve system 15. Another conduit 32 leads from the lower portion of the chamber 19 to divert cold water into the mixing valve system 15, as is clearly shown in FIGURE 1. The mixing valve assembly 15 is provided with an outlet conduit 33 and with an adjustable proportioning valve assembly 34 of generally conventional construction for adjusting the proportions of the hot and cold water admitted through conduits 30 and 32 allowed to pass to the outlet conduit 33. The mixing valve system 15 may be provided with a manually-operated mixture-adjustment knob 35, or alternatively, may be provided with a conventional thermostatically-controlled, manually-settable mixing valve mechanism, if so desired.

Boiler chamber 21 has a top wall 36, and rising from said top wall adjacent the vertical wall of tank 16 is a generally cylindrical vertical chamber 37 having a top wall 38 provided with a conventional safety valve 39. Concentrically-secured inside the chamber 37 is another cylindrical shell element 40 (FIGURE 7), and slidably and rotatably-disposed between shell 40 and main cylindrical chamber 37 is a sleeve 41. Sleeve 41 is provided at its upper portion with an aperture 42 which is registerable with an aperture 43 provided in shell 40 when the sleeve 41 is in a relatively elevated position. Aperture 43 registers with an aperture 44 provided in the upper portion of the wall of chamber 19. Thus, when aperture 42 is in registry with the apertures 43 and 44, communication is established between the interior of shell 40 and the upper portion of chamber 19.

Sleeve 41 is provided with an aperture 45 in its lower portion which is registerable with a pair of registering apertures 46 and 47 provided, respectively, in shell 40 and the cylindrical outer wall 37, as shown in FIGURE 7, when the sleeve 41 is in a lowered position, thus allowing steam from the upper portion of boiler 21 to vent freely to atmosphere. When the sleeve 41 is raised to a position wherein aperture 42 registers with apertures 43 and 44, the vent aperture defined by the openings 46 and 47 is substantially sealed.

Sleeve 41 is vertically moved by the action of a float ball 48 rigidly-secured to the end of a float rod 49, the float rod having an intermediate bearing ball 50 which is rotatably-supported in a socket assembly 51 mounted in the wall of tank 16, as shown in FIGURE 6. The end of rod 49 is provided with a lug 52 secured to sleeve 41 and slidably-engaged in an arcuate slot 53 provided therefor in the cylindrical wall 37. An inwardly-projecting headed button 54 slidably-engages in an arcuate track 55 provided on the interior surface of shell 40, the button 54 being connected to the lug 52 and having a shank which extends through an aperture provided therefor in the sleeve 41, so that the sleeve follows the movements of the button 54 and is guided through said movements by the provision of the registering arcuate slot 53 and arcuate trackway 55. The arcuate slot 53 and arcuate trackway 55 are concentric with the ball 50. Thus, movement of the float ball 48 in response to changes in the level of the water in chamber 19 causes inverse corresponding move-

ments of the valve sleeve 41. When the water level drops below a predetermined safe amount, aperture 42 is moved into registry with apertures 43 and 44, allowing steam from boiler 21 to enter the upper portion of chamber 19, to cause replenishment of the water by pumping action, as will be presently described. When the water level in chamber 19 rises to a predetermined top-limiting value, aperture 45 registers with apertures 46 and 47, allowing free venting of the steam from chamber 21 to atmosphere while, at the same time, closing off the apertures 43 and 44. This latter condition is illustrated in FIGURE 7. The provision of the safety valve 39 prevents excessive build-up of steam pressure by allowing the steam to release when a predetermined upper safe-limiting pressure is reached.

Tank 16 is provided with an emergency water-heating means which may be employed in the event of a power failure such as the failure of a power supply employed for the electric heating device 24. Thus, the bottom wall 23 of chamber 19 is formed with a depending well 56 which may be heated by any suitable heating means, such as a portable gas burner, or the like, which may be positioned or mounted in any suitable manner beneath the well 56. The auxiliary burner is designated at 57 in FIGURE 1, and this burner is of any conventional type arranged to be energized by connecting thereto a suitable portable source of fuel, not shown.

The horizontal partition wall 17 is formed with a valve opening 58, and pivoted in this opening is a generally circular valve disc 59, the disc having the transverse pivotal axle 60 whose ends are supported in opposite marginal portions of opening 58, as shown in FIGURE 4. The opening 58 has the inwardly-projecting marginal lip 61 at one side of its upper portion and an inwardly-projecting marginal lip 62 at the other side of its lower portion, and the disc is correspondingly recessed to sealingly-receive the marginal lips 61 and 62. Thus, the lips 61 and 62 act as limiting means to prevent rotation of the disc 59 past its horizontal sealing position shown in FIGURE 2. Disc 59 may be rotated to an open position, such as that shown in dotted view in FIGURE 2, and in full-line view in FIGURE 1. Disc 59 is actuated by a rod 63 pivotally-connected to the disc at 64, the disc being formed with a radial slot 65 which receives the flattened lower end portion 66 of rod 63, as shown in FIGURES 2, 4 and 5. The wall of slot 65 is formed with the respective detent recesses 67 and 68 spaced angularly relative to transverse pivot pin 64 by approximately 90°, and being adapted to be lockingly-and-releasably-engaged by a ball detent 69 disposed in a recess 70 provided in the end of flattened rod portion 66 and biased outwardly by a spring 71, as shown in FIGURE 5. Thus, the ball detent 69 engages either in the recess 67 or in recess 68, to lock the disc 59 either in the horizontal closed position thereof of FIGURES 2 and 3, or in the open position thereof shown in FIGURE 1, or in dotted view in FIGURE 2. The ball 69 is yieldable responsive to a relatively moderate force applied to the rod 63, in a manner presently to be described.

Rod 63 may be made of any suitable material, such as solid rigid plastic rod material. The top end of rod 63 is tightly-secured in a depending sleeve 72, which may be made from copper tubing, or the like. The top left corner of sleeve 72, as viewed in FIGURE 2, is hinged at 73 to the underside of a valve block 74 mounted on the top wall 20 of upper chamber 18 over a vent opening 75 provided in said top wall. The valve block 74 comprises a body of suitable relatively-flexible material, such as hard rubber, or the like, formed with a stationary stop portion 76, which may be of generally triangular longitudinal cross-section, as shown in FIGURE 2, and which is formed with a groove or recess 77 which tightly-receives a marginal portion of the opening 75 in top wall 20, thus securing the block 74 in its operating position shown in FIGURES 1 and 2. The block

74 has the movable flap valve portion 78 which is rotatable relative to the stationary stop portion 76 around the axis of a transverse hinge element 79 provided between the lower end portions of the rear face 80 of flap 78 and the inclined front face 81 of stop element 76.

The underside of the flap member 78 is formed with a depending hollow annular rib 82 surrounding the hinged top end portion of sleeve 72, the interior of rib 82 being filled with air. The flap block 78 is provided with a sealed metal capsule 84 located above the hollow rib 82, the capsule being of copper, or other suitable metal, and a quantity of mercury 85 is contained therein. Rigidly-secured to the flap block 78 immediately beneath capsule 84 and depending into the top end of sleeve 72 is a downwardly-projecting inclined stop pin 86 which serves as a means to guide the swinging movement of sleeve 72 relative to the valve flap block 78. As shown in FIGURE 3, the guide pin element 86 may have an arcuate cross-sectional shape to conform with the inside contour of sleeve 72. The mass of mercury 85 serves a special function in that its acts as a triggering means to cause the flap block 78 to swing downwardly from the open dotted-view position thereof shown in FIGURE 2 to the closed full-line view position thereof responsive to the expansion of the mercury when exposed to steam. Actually, as will be presently described, the heat transfer takes place through the relatively thin highly-conductive wall of the capsule 84, and the location of the capsule is such that the expansion of the mercury causes a mechanical imbalance of sufficient degree to overcome the forces acting to support flap block 78 in its open position. Specifically, there forces comprise the resistance of the detent recess 68 to the biasing force of the ball detent element 69 and the biasing spring 71 associated with the detent ball 69, together with a practically negligible upward force exerted on the block 78 by the steam flowing through opening 75 from chamber 18. As will be presently explained, the closing action of block 78 is assisted by the fact that condensation of steam takes place in chamber 18, producing a vacuum therein, whereby atmospheric pressure cooperates with the expanding action of the mercury mass 85 to move the valve flap block toward its closed position.

The stop member 76 limits the upward movement of the flap element 78 substantially to the dotted position thereof shown in FIGURE 2, and the full-view position thereof shown in FIGURE 1. As will be presently explained, in order to rotate the flap block element 78 upwardly from the full-line position thereof of FIGURE 2 to the dotted-view position thereof, among other things, it is necessary to overcome the resistance to movement provided by the action of detent ball 69 on recess 67. As will be presently explained, this is accomplished by the building up of fluid pressure in the upper portion of chamber 18 resulting from the filling up of said chamber with liquid from the source 12 drawn into the chamber by suction.

In operation, as the level of the water, shown at 90 in FIGURE 1, in the lower chamber 19 drops, the ball 48 moves downwardly and eventually reaches a bottom-limiting position wherein sleeve 41 is elevated so as to move opening 42 into registry with apertures 43 and 44 (FIGURE 7). Steam from boiler 21 then is allowed to pass into the upper portion of chamber 19, and thence through opening 58, normally uncovered, into the upper chamber 18. The steam passes upwardly through the top opening 75 and flows past the underside of the flap block 78, heating the capsule 84, and eventually causing the mass of mercury 85 therein to expand, whereupon the mercury mass shifts its center of gravity rightwardly, as viewed in FIGURE 1, sufficiently to cause it to exert a downward force sufficient to overcome the holding action of detent ball 69 relative to recess 68.

It will be seen from FIGURE 2 that in the open position of the lower valve disc 59, the valve disc is slightly

off dead-center position, so that it can readily rotate in a clockwise direction from the dotted-view position thereof of FIGURE 2 toward the full-line position thereof, responsive to a relatively moderate downward force exerted on the rod 63.

The downward rotation of valve flap block 78 from the dotted-view position thereof to the full-line position thereof in FIGURE 2 simultaneously swings the bottom valve disc 59 to its closed position, so that both the upper valve element and the lower valve element of the tandem-valve system close simultaneously. Previously, the steam entering the upper chamber 18 has replaced all the air in said upper chamber, which escapes out through the opening 75, so that when the valve flap block 78 closes, there is only a relatively small amount of air left in chamber 18. After closure of the flap block 78 and the bottom valve disc 59, the steam in chamber 18 continues to condense (the condensation of the steam commencing even before the closure of valve flap element 78) so that a vacuum is formed in chamber 18 which causes water to be drawn into the chamber from the source 12 through the conduit 13. The vacuum is tightly held by the expansion of hollow annular rib 82 caused by the pull of the vacuum acting relative to the pressure of the air inside the hollow rib 82. As the vacuum in chamber 18 is reduced responsive to the filling of the chamber with water, the suction pull on the hollow rib 82 diminishes, becoming entirely released substantially as the water level reaches and exerts buoyant force on said hollow rib. The water rises in chamber 18 until it comes into contact with the copper tubing 72, which is in thermal contact with the capsule 84, whereby heat is conducted away from the capsule to a sufficient extent to cool the mercury 85 and contract it sufficiently so that flap block 78 is swung upwardly by the building up of the fluid pressure in the top portion of chamber 18 (compression of the small amount of retained air and vapor in the upper portion of the chamber). The upwardly-swinging movement of the flap block element 78 is facilitated by the shift of the center of gravity of the contracted mercury 85 to the left, as viewed in FIGURE 2. The upward force exerted on flap block element 78 is sufficient to overcome the resistance of detent ball 69 with respect to recess 67 as well as the gravitational force of the elements of the tandem-valve assembly. The re-opening of the bottom valve disc 59 allows the water admitted to chamber 18 to flow downwardly through opening 58 into the bottom chamber 19. Sufficient water is in this way admitted so that the float ball 48 rises sufficiently to close the steam-admission passages 43, 44 by the descent of sleeve element 41 to its sealing position, such as that shown in FIGURE 7, and to simultaneously move the sleeve aperture 45 into registry with the openings 46, 47 to allow steam to vent freely to the atmosphere. The parts thus return to the normal positions thereof shown in FIGURE 1, and remain in these positions until pumping action is again required, for example, by the dropping of the level of the water 90 in the lower chamber 19, as above-described.

As above-mentioned, condensation begins as soon as steam enters the upper chamber 18, whereby the pressure in the upper chamber 18 begins to drop and becomes less than atmospheric shortly after the steam has been admitted thereto through opening 58. Thus, shortly after the major portion of the air in chamber 18 has been released through opening 75, atmospheric pressure begins to act on the valve flap block 78. This combines with the shifting of the center of gravity of the expanded mass of mercury 85 to cause the flap element 78 to be lowered to closed position. The vacuum developing in chamber 18 also acts on the underside of the annular hollow rib 82, as well as on the remaining bottom surface portion of flap element 78 to urge the flap element downwardly. The fact that the annular rib 82 is hollow and air-filled makes it buoyant, so that in the event the

water level in chamber 18 rises so that it begins to approach top wall 20, the buoyancy of the rib 82 insures the opening of valve block element 78 before chamber 18 becomes completely filled.

The flap valve element 74 is normally open, namely, is in the dotted-view position thereof shown in FIGURE 2, and remains open except when pumping action occurs responsive to the drop in level of the liquid 90 in the lower chamber 19 to a bottom-limiting value such as to cause the valve sleeve aperture 42 to move into registry with the apertures 43 and 44, as above-described.

The capsule 84 which extends substantially horizontally in the closed position of the valve element 78 is thus in an inclined position in the normal state of the flap valve element 78, as shown in FIGURE 2 in dotted view. The hinge connection 73 is located approximately one-third the distance between the lower and upper ends of the capsule, as seen in dotted section in FIGURE 2. Thus, the distance between the hinge connection 73 and the lower end of the capsule is approximately one-third the entire length of said capsule. The major portion of the mercury 85, in its cold condition is, therefore, located between the hinge connection 73 and the lower end of the capsule. When the capsule is exposed to the hot vapor escaping through the opening 75, as above-described, the mercury 85 expands sufficiently so that a considerable quantity thereof extends outwardly past the pivot connection 73 in the direction of the free end of the flap valve element 78, and the weight of the expanded mercury is thus sufficient to overcome the relatively light holding resistance provided by the spring-biased detent ball 69 in cooperation with the detent recess 68.

As will be readily apparent, the liquid pumping mechanism above-described has substantially universal application and can be readily employed for pumping water or, with minor changes, for pumping gas, oil, or other fluids.

While a specific embodiment of an improved fluid pump has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A liquid pump comprising an upstanding tank having an upper chamber and a lower chamber with a partition wall between said chambers, a liquid-inlet conduit connected to said upper chamber, said inlet conduit leading to a supply source of liquid, a liquid-outlet conduit connected to said lower chamber, means to generate hot vapor in the upper portion of the lower chamber, said upper chamber having a top wall, tandem-coupled valves in said top wall and said partition wall, said tandem-coupled valves being normally open, means to close the tandem-coupled valves at times responsive to exposure thereof to hot vapor, whereby to trap condensing vapor in the upper chamber and produce vacuum therein and to draw liquid from the source into the upper chamber through the inlet conduit, and means to re-open the tandem-coupled valves responsive to the reception of a substantial quantity of liquid in said upper chamber.

2. A liquid pump comprising an upstanding tank having an upper chamber and a lower chamber with a partition wall between said chambers, a liquid-inlet conduit connected to said upper chamber, said inlet conduit leading to a supply source of liquid, a liquid-outlet conduit connected to said lower chamber, a liquid boiler, means communicatively-connecting the lower portion of the lower chamber to the boiler to furnish liquid thereto, vapor-admission valve means between said boiler and the upper portion of the lower chamber, means operating said vapor-admission valve means in accordance with the liquid level in said lower chamber, said upper chamber having a top

wall, tandem-coupled valves in said last-named top wall and said partition wall, said tandem-coupled valves being normally open, said vapor-admission valve means being constructed to admit hot vapor from the boiler into the upper portion of the lower chamber responsive to a predetermined low level of liquid in said lower chamber, means to close the tandem-coupled valves responsive to exposure thereof to the hot vapor, whereby to trap condensing vapor in the upper chamber and produce vacuum therein and draw liquid from the supply source into the upper chamber through the inlet conduit, and means to re-open the tandem-coupled valves responsive to the reception of a substantial quantity of liquid in said upper chamber, whereby to refill the lower chamber responsive to the re-opening of said tandem-coupled valves.

3. The liquid pump of claim 2, and wherein the means operating the vapor-admission valve means comprises a float member in the lower chamber, and means mechanically-coupling the float member to the vapor-admission valve means.

4. The liquid pump of claim 2, and wherein the vapor-admission valve means comprises a vertical conduit communicating with the top of said boiler and secured to the side-wall of the lower chamber, with a communication port between the vertical conduit and the upper portion of the lower chamber, an apertured valve sleeve slidably-mounted in the vertical conduit, a float member in the lower chamber, and means mechanically-coupling said float member to said apertured valve sleeve, said sleeve having an aperture registrable with said communication port responsive to the descent of said float member to a predetermined height in said lower chamber.

5. The liquid pump of claim 2, and wherein said tandem-coupled valves comprise a first flap valve element pivoted over an aperture formed in the top wall of the upper chamber, a second flap valve element pivoted in an aperture formed in the partition wall, and link means interconnecting said flap valve elements.

6. The liquid pump of claim 5, and wherein the tandem-coupled valves are provided with yieldable detent means releasably-holding the tandem-coupled valves either in fully-opened or fully-closed positions and wherein said means to close the tandem-coupled valves comprises a substantially longitudinally-extending metal capsule in the first flap valve element containing a quantity of fluid material thermally-expansible longitudinally away from the link connection to the first flap valve element responsive to heat sufficiently and in a direction to overcome the holding force of the detent means.

7. The liquid pump of claim 6, and wherein the metal capsule is provided with a depending heat-conducting metal portion extending into the upper portion of the upper chamber and engageable by liquid to cause the capsule to be cooled.

8. The liquid pump of claim 7, and wherein the first flap valve element is provided with a depending hollow buoyant portion engageable by liquid in the upper portion of the upper chamber to exert upward opening force thereon.

9. The liquid pump of claim 8, and wherein said depending heat-conducting metal portion forms the upper part of said link means.

10. The liquid pump of claim 9, and wherein said hollow buoyant portion comprises an annular hollow air-filled rib depending from said first flap valve element and surrounding said depending heat-conducting metal portion.

11. The liquid pump of claim 10, and wherein said depending heat-conducting metal portion comprises a metal tube hingedly-connected at a top edge portion thereof to the underside of said first flap valve element.

12. The liquid pump of claim 11, and a stop pin element depending from said capsule into the metal tube and

being engageable therewith to limit relative movement of
the first flap valve element with respect to said metal tube.
